BOX FOR PERFUMES, BATH SALTS, SMELLING
SALTS OR THE LIKE

Jago Dreiding, Monchhofstrasse 14, Kilchberg,
Zurich, Switzerland

Filed June 16, 1960, Ser. No. 60,990

Term of patent 14 years

(Cl. D58—11)

FIG. 1 is a side elevational view of a box for perfumes, bath salts, smelling salts or the like, showing my new design;

FIG. 2 is a top plan view;

FIG. 3 is an elevational view of the box taken when rotated 90° from the position of FIG. 1; and

FIG. 4 is a bottom plan view thereof.

I claim:

The ornamental design for a box for perfumes, bath salts, smelling salts or the like, as shown.
